[57] CLAIM

The ornamental design for recreational ball, as shown and described.

DESCRIPTION

FIG. 1 is a perspective view of a first embodiment of a recreational ball showing our new design;

FIG. 2 is a front view of FIG. 1;

FIG. 3 is a top plan view of FIG. 1;

FIG. 4 is a side view taken from the left of FIG. 2;

FIG. 5 is a side view taken from the right of FIG. 2;

FIG. 6 is a bottom plan view of FIG. 1;

FIG. 7 is a rear view of FIG. 1;

FIG. 8 is a perspective view of a second embodiment;

FIG. 9 is a front view of FIG. 8;

FIG. 10 is a top plan view of FIG. 8;

FIG. 11 is a side view taken from the left of FIG. 9;

FIG. 12 is a side view taken from the right of FIG. 9;

FIG. 13 is a bottom plan view of FIG. 8; and,

FIG. 14 is a rear view of FIG. 8.

The drawing is lined to indicate contrasting color.
